UNITED STATES PATENT OFFICE

2,438,240

METHOD FOR STRAIGHTENING RODS

André Joseph Trudeau, Waterbury, Conn., assignor to Chase Brass & Copper Co. Incorporated, Waterbury, Conn., a corporation

Application September 28, 1945, Serial No. 619,136

1 Claim. (Cl. 153—60)

1

This application relates to improved methods for straightening rods, and more particularly to straightening metal rods.

One object of this invention is to provide an improved method by which a much higher output can be obtained than can be obtained by the construction made in accordance with Medart Patent No. 558,591, patented April 21, 1896.

Another object of this invention is to provide an improved method by which a higher output of straightened rods can be obtained.

With the above and other objects in view, as will appear to those skilled in the art from the present disclosure, this invention includes all features in the said disclosure which are novel over the prior art.

In the description and claim, the various parts and steps are identified by specific terms for convenience, but they are intended to be as generic in their application as the prior art will permit.

In the accompanying drawings forming part of the present disclosure, in which one way of carrying out the invention is shown for illustrative purposes:

Fig. 1 is a top plan view illustrating one way of carrying out the present invention;

Fig. 2 is a front elevation of Fig. 1;

Fig. 3 is a right end view of Fig. 2;

Fig. 4 is a sectional view on line 4—4 of Fig. 2; and

Fig. 5 is a sectional view on line 5—5 of Fig. 2.

Referring to the drawings, the rolls 10 and 11 could be respectively mounted in place of the rolls X and Y shown in the Medart Patent No. 558,591, with their longitudinal axes arranged in angularly crossed relation to one another. The roll 10 is a convex roll having shafts 12 and 13 at its opposite ends for supporting it for rotation in suitable bearings (not shown), the shaft 13 having any suitable driving portion as 14 suitable to be drivably connected to any suitable driving-means (not shown) for rotating the roll 10. Similarly, the concave roll 11 has shafts 15 and 16 at its opposite ends for supporting it for rotation in suitable bearings (not shown), the shaft 16 having any suitable driving portion 17 to be drivably connected to any suitable driving-means (not shown) for rotating the roll 11.

Merely for convenience of reference in the claim, the term "median plane" will be used. The median plane is defined or explained as that imaginary horizontal plane indicated by the line 18 (Figs. 2 and 3) which extends through the centers of both of the rolls 10 and 11 between and

2

at equal distances from the ends of the two driving portions 14 and 17 of the two rolls.

An upper rod-guide 19 and a lower rod-guide 20 are mounted in adjustable position in any suitable way as, for example, in the previously-mentioned Medart patent. It will be noted that except for the entrance and exit portions of the guides 19 and 20, their respective opposite guide-faces 21 and 22 extend in approximately parallel planes as most clearly illustrated in Figs. 2 and 3, and which planes are also parallel to the median plane 18.

The rods 23 and 24 which are to be straightened are fed in from the left end of Figs. 1, 2, 15 4 and 5, and owing to the arrangement of the rolls 10 and 11 and their directions of rotation as indicated by the arrows, the rods 23 and 24 are both rotated and straightened as they are fed toward the right. Thus, with regard to the rod 23, while it does not contact all portions of the rolls 10 and 11 at any given instant, it is engaged between the convex surface 25 of the roll 10 and the concave surface 26 of the roll 11 and the guide-face or surface 21 of the upper 25 rod-guide 19 as it travels to the right and is straightened. And similarly, as the rod 24 travels to the right and is straightened, it engages or is in contact with the surfaces 25 and 26 respectively of the rolls 10 and 11 and the guide-face 22 of the lower rod-guide 20.

In the claim, the rod-guides are stated as being located between the rolls and at opposite sides of the median plane of the rolls. The term "at opposite sides" does not have any significance as to horizontal or vertical, but merely as to relative relation as concerned with the median plane.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claim are 40 intended to be embraced therein.

I claim:

The process of simultaneously straightening two rods or the like including: passing two rods 50 in the same general direction longitudinally into rod-straightening mechanism having a pair of straightening-rolls arranged adjacent but spaced apart from one another and rotating in the same direction of rotation about their respective longitudinal axes, which said axes are arranged in 55 angularly crossed relation to one another, and

which said mechanism has two rod-guides located between said rolls and at opposite sides of the median plane of said rolls and spaced apart from one another, and which said rolls and guides simultaneously support, rotate, feed longitudinally, guide and thereby straighten said two rods at opposite sides of said median plane and spaced apart from one another with each said rod in contact with both of said rolls and one of said guides.

ANDRÉ JOSEPH TRUDEAU.
